MEANS FOR CONTROLLING CARD PERFORATING MACHINES

Louis Frank Woodruff, Brighton, Mass., and Martin L. Nelson, Park Ridge, Ill.; said Nelson assignor, by mesne assignments, to Associated Electric Laboratories, Inc., Chicago, Ill., a corporation of Delaware, and said Woodruff assignor to Central Records, Inc., Chicago, Ill., a corporation of Delaware

Application June 17, 1929, Serial No. 371,417
Renewed June 17, 1933

42 Claims. (Cl. 164—113)

The present invention relates, in general, to means for controlling card perforating machines, such as the Hollerith and the Powers perforating machines.

5 The main object of the present invention is to provide means whereby two similar mechanical card perforating machines may be simultaneously operated to punch different types of cards.

10 One of the features of the invention relates to the means whereby one of the card perforating machines is operated to double punch its card in coded perforations while the other machine is operated to single punch its card.

15 A further feature of the invention relates to the storing and code punching arrangement between two similar card perforating mechanisms which permits the same information to be simultaneously punched in two cards, one of the cards being double punched in code and requiring 20 only one-half of the space that is required on the other or the single punched card.

25 The foregoing and other features not specifically mentioned may be described more in detail by referring to the drawings comprising Figs. 1 to 6, which diagrammatically show a sufficient amount of apparatus used to enable the invention to be described and understood.

30 Fig. 1 diagrammatically shows the general layout of an accounting system using merchandise display and inventory cards of the above type for articles purchased by a department store.

35 Fig. 2 shows a merchandise display card, which is double punched in code and which is fastened to the article for sale to accompany such article to the sales floor of the department store.

40 Fig. 3 shows an inventory card for an article of merchandise. This card is single punched simultaneously with the merchandise display card and is filed in the inventory file when the article is sent to the sales floor.

45 Fig. 4 shows a chart by means of which the double code perforations in the display card may be translated to correspond to a portion of the single punchings on the inventory card.

50 Fig. 5 shows the circuit arrangements, magnets and relays for controlling the perforating machine which single punches the inventory cards.

55 Fig. 6 shows the circuit arrangements, magnets, and relays for controlling the perforating machine which double punches the merchandise display cards. The two machines are mechanically similar to the perforating machine disclosed in Patent No. 1,305,557, issued June 3, 1919, to W. W. Lasker. However, in the present invention electric circuits have been designed to elec-

trically control the two machines as will be explained more fully hereinafter.

Fig. 7 shows a side view in part of one of the two machines.

Fig. 8 shows a sectional view of one of the two machines.

5 In the present invention when articles of merchandise are ordered by a department store from a manufacturer or vendor an inventory card is made out for each article and punched with all 10 the required data relating to such an article. A merchandise tag or card is also made out for each article and when the article is received the card is attached thereto before it is sent to the sales floor. The merchandise card of the present invention is preferably smaller than the inventory card for various reasons, one of which is that it is made for use with a system such as disclosed in the M. L. Nelson application Serial No. 275,643, filed May 7, 1928, and therefore the card is to be 15 perforated in such a manner that it contains a part of the same data that is perforated in the inventory card. In order to save time and possible errors both the inventory card and the merchandise card are perforated at the same time 20 by two similar card perforating mechanisms which are controlled by a single set of control keys.

25 However, since the merchandise card is considerably smaller than the inventory card one of 30 the card perforating mechanisms is arranged to code punch the merchandise card with double perforations in the limited space on the merchandise card in order to punch the same data that is punched on the inventory card. Fig. 1 diagrammatically shows how the inventory cards are fed 35 through a tabulator of the Powers type to print lists in accordance with the perforations in the cards; which lists may be checked against the copy of the order and the invoice to guard against 40 any possible errors which may occur in the punching operation.

Fig. 2 shows in detail the merchandise display card 45 which is both printed and punched with the store department number, the sales price, the serial number, the size, the color, and the classification of the article. The merchandise card is slightly indented along the line X to weaken the same so that the upper portion of the card containing the hole 12 may be detached 50 from the lower portion containing the punched information. The hole 12 is used for fastening the card by means of a string to the article to be sold. The merchandise display card is divided 55 into ten horizontal rows numbered 0 to 9 con-

secutively from bottom to top, and into ten vertical columns numbered 1 to 10 consecutively from left to right. The dot-dash line Y divides the card into upper and lower sections so that 5 each vertical column has an upper and a lower field in which the coded perforations corresponding to numerals may be made.

Fig. 3 shows in detail an inventory card which is provided for each article purchased by the department store. Each inventory card is divided 10 into forty-five vertical columns numbered 1 to 45, consecutively, from left to right, and is divided into ten horizontal rows numbered 0 to 9 consecutively from top to bottom. This card is divided 15 into fields for designating certain information when perforated therein. For instance, the first field comprising vertical columns 1, 2, and 3 designates the month and day the article was purchased, the second field including columns 4, 5, 6, 20 and 7 designates the department store number of the order, the third field including columns 8, 9, 10, and 11 designates the code number of the manufacturer to whom the order was sent, the fourth field including columns 12, 13, and 14 25 designates in coded form the date received by month and season so that at a later date the store manager or buyer is enabled to find out how long the article has been on the sales floor and whether the article is in season. The fifth field comprising columns 15, 16 and 17 is for use when 30 the price of an article has been marked down for special sale or other cause, the column 15 indicating the number of times the article has been marked down and columns 16 and 17, the 35 reason why such article is marked down. In a similar manner the remaining columns are divided into fields as shown by heavy lines to designate the department number, classification of article, the cost price, the sales price, the serial number, the size, the color, the kind of material, 40 and the style of the article.

The inventory card 11 is single punched with a single perforation in each vertical column to designate numerals corresponding to certain data 45 dependent upon the fields in which the perforations appear. In order that the merchandise card be punched with the same information as the inventory card, it is necessary that each vertical column in the merchandise card have perforations therein which will correspond to two numerals instead of one numeral because of the 50 limited space on the merchandise card. Each vertical column of the merchandise card is therefore divided into two sections, an upper section 55 or field and a lower section or field. Since each field of each vertical column has perforation spaces less in number than the number of numerals which are to be designated, the various numerals are represented in code, that is, each 60 numeral is represented by two perforations. Successive numerals in the merchandise card are designated by combination perforations in the upper and then the lower fields of each successive 65 vertical column. The code for perforating the merchandise card is clearly shown in Fig. 4.

Referring now to Figs. 7 and 8, the mechanical operation of the two punching machines is preferably the same as disclosed in United States Letters Patent, No. 1,305,557, to which reference 70 can be had for details not here deemed necessary to described. Generally the feeding means for the card may be any suitable construction for successively removing the cards one at a time from a stack and delivering them to feed rollers 75 715. The cards are delivered to the rollers 715

by a block which is operated in timed relation to the cycle of operations by means of connection with the main shaft 185. The cards delivered from the card magazine enter a passage 724 of the punching unit 711 and abut an automatically operated stop 725 which locates the card punching positions in position respectively with punches 726 on one side and holes 727 in a die 728 on the other side. The punches 726 are guided at their lower ends by a plate 730 which moves with the die 728 and the arrangement is such that when the card engages with the punches which are not set such punches will be pressed back by the card and die without making perforations, while the punches which have been set will perforate 15 the card because these punches are locked in operated position.

The perforating selecting means or set-up bars 731 are slidably mounted in a fixed frame 732, each being notched to form a cam acting latch 20 733 which, upon movement of the bar 731, shifts a laterally movable latch plate 734 so that any selected set up bar 731 will be held down and locked during the punching operation. Below the set up frame 732 is a cage 734' holding a plurality of slidable punch engaging pins 735, the number corresponding to the number of set-bars 731 and the arrangement being such that each pin 735 is in alinement with a set-bar 731 at its upper end and with a punch 726 at its lower end. 30 The pins 735 are respectively held projected into engagement with the set-bars 731 by springs 736 so that each is automatically returned to normal position, with its lower end spaced from its punch, and also returns its bar 731 when the latter is 35 released after the punching operation. The punches 726 are similarly arranged and correspond to the number and arrangement of the set-bars 731 so that whenever a pin 735 is held locked and projected into engagement with its punch 40 head that particular punch will be rigidly held against movement imparted by the die 728.

The selection and setting of the perforating selecting means or set-up bars 731 is accomplished by a carriage 737, which is arranged to 45 travel by a step-by-step movement to successive rows or groups of set-up bars 731. This carriage is provided with a plurality of spring pressed plungers 738 corresponding in arrangement and number to a record column of the inventory card, 50 which in the preferred form is made up of twelve record positions representing numbers. Associated with each plunger 738 is a flexible rod 750 extending to a solenoid magnet and arranged so that the energization of the solenoid magnet 55 moves the rod to cause the operation of its associated plunger 738. In the first machine there is provided a key, such as key 102, for each solenoid magnet, such as magnet 122 while the magnets of the second machine are controlled by the same 60 keys and relays such as relays 230 to 238, inclusive, and relays 141 to 150, inclusive, as will be more fully described hereinafter.

In the operation of the punching unit, the carriage 737 travels longitudinally step-by-step 65 across the rows of set-up bars 731 stopping momentarily over each row so that the actuation of any of its plungers 738 will cause a set-up bar 731 to project its pin 735 into the path of the alined punch 726. In the present invention the 70 escapement mechanism of the first machine is operated to advance the carriage one step responsive to a single actuation of one of the keys while in the second machine the escapement mechanism is similarly operated to advance the 75

carriage one step responsive to two actuations of a key or keys because only the second actuation of a key operates the magnets, as will be more fully explained hereinafter.

5 When the complete set-up is made, the trip key TR is depressed to control the actuation of the machine so that the die 728 rises to bring the card into punching relation with the punches and those which are rigidly held by the set pins 735 are caused to perforate the card. The reciprocation of the die 728 takes place in timed relation with the rotation of the shaft 185 after which the cards are moved out of the punching machines into their card hoppers in a well known manner.

10 Having described the system and the apparatus to be used, a detailed description will now be given of the operations necessary to punch the inventory and merchandise cards.

15 The punch operator, upon receiving a copy of a merchandise order, will first close the knife switch 198 to start the motors 197 and 297 of the respective punches shown in Figs. 5 and 6. The punch operator now operates the keys of the key board in accordance with the data on the merchandise order. The operator, therefore, operates key 103 and then key 101 twice in order to punch the inventory card 11 (Fig. 3) in vertical columns 1, 2, and 3 with the date of purchase.

20 Responsive to the operation of key 103 a circuit may be traced as follows for energizing the punch magnet 123: From ground by way of repeat switch spring 181 and its resting contact, key 103, magnet 123, conductor 100, terminal 178, and battery 25 at lever 176. Relay 143 energizes in parallel with magnet 123 and at armatures 157 and 158 connects the common conductor 116 to conductors 201 and 205. The closure of these contacts are without effect at this time because the control springs 172 are not closed in this position of the punch carriage. Magnet 123, upon energizing, sets the perforating means or pins of the punch so as to punch the inventory card in horizontal row 3 in vertical column 1. When the key 103 is released, relay 143 and magnet 123 deenergize.

30 The deenergization of the magnet causes the carriage, due to its escapement mechanism, to move one step so that the carriage is in position to set the next row of perforating means to punch the inventory card in the second vertical column.

35 Responsive to the operation of key 101 relay 141 and punch magnet 121 energize from ground at spring 181 over conductor 100 and battery at lever 176. Relay 141 at armatures 153 and 154 connects the common conductor 116 to conductor 201 and conductor 203. This operation, at this time, is also ineffective because the common conductor 116 is not connected to the common grounded conductor 200. Magnet 121 operates

40 and sets the perforating means to punch the inventory card in horizontal row 1 in vertical column 2 and upon the release of key 101 the magnet and relay release; and the magnet, in the well known manner, causes the carriage to take another step.

45 The same operation just explained takes place responsive to the second actuation of the key 101. The perforating means of the punch is now set to punch the inventory card in accordance with the date of the purchase of the merchandise, which in this case, is the third month or March and the eleventh day of the third month.

50 The operator again refers to the copy of the order and now operates the keys in accordance with the number of the order, which in this case

5 is order No. 2345. The operator accordingly operates the keys 102, 103, 104, and 105, thereby causing the punch magnets 122, 123, 124, and 125 in the order named to set the perforating means to punch the inventory card in vertical columns 4, 5, 6, and 7 in horizontal rows 2, 3, 4, and 5, respectively. Relays 142 to 145, inclusive, also energize in parallel with the punch magnets but their operations are ineffective because the control springs 172 are still open. Responsive to the 10 operation of the magnets the carriage of the punch has been stepped to position 8 ready to set the next row of perforating means to punch the inventory card in vertical column 8. In a similar manner the operator again refers to the copy 15 of the order and operates the keys in accordance with the code number of the manufacturer to whom the order was sent, or in this case No. 4321. Responsive to this operation the perforating means is set to punch the inventory card 11 in 20 columns 8, 9, 10 and 11 as illustrated in Fig. 3. In case the merchandise on the above-mentioned order has not been received at the time that the operator is punching the cards, the vertical columns 12, 13, and 14 are left blank, or in other 25 words, the operator pushes the skip key three times to cause the carriage to move to position 15 without setting the perforating means of rows 12, 13 and 14. By the operation of the skip key the skip magnet is operated to operate the escape- 30 ment of the carriage to take one step for each actuation thereof in a well known manner. In a similar manner the operator operates the skip key to cause the carriage to move to position 17.

35 When the carriage of the punch (Fig. 5) reaches its seventeenth position the control bar 171 has been moved to the right a sufficient distance to close the control springs 172. The closure of the control springs 172 connects the grounded conductor 200 to the common conductor 116 so that 40 the operation of the relays such as relay 150 are effective to now close operating circuits over the conductors 201 to 205, inclusive.

45 The operator now operates the keys 110, 102, 101, and 110 in succession in the order named in order to punch both the merchandise tag or card 10 and the inventory card 11 with the mark-down reason number, if any, the department number for which the merchandise or goods was purchased, and in accordance with the classification 50 of the article bought. Responsive to the operation of key 110, magnet 130 and relay 150 are energized by way of the grounded conductor 200. Magnet 130 operates and sets the perforating means to punch the inventory card in horizontal 55 row "0" in vertical column 17 to indicate that this article has not been marked down. Relay 150, upon energizing, at armatures 151 and 152 closes circuits for energizing relays 230 and 231 (Fig. 6) as follows: from grounded conductor 200, through control springs 172 which are now closed, conductor 116 and thence by way of armatures 151 and 152 over conductor 201 and conductor 202 and armatures 252 and 253 and their resting contacts to relay 230 and relay 231 to 60 battery. Relays 230 and 231, upon energizing, at armatures 239 and 241 complete locking circuits for themselves in series with relay 238 and grounded armature 249 and at armatures 240 and 242 prepare circuits for operating magnets 70 229 and 228. Relay 238 does not immediately energize in series with relays 230 and 231 because relay 238 is short circuited from the ground connected to conductor 116. When the operator releases the key 110 magnet 130 and relay 150 75

deenergize. Responsive to the deenergization of magnet 130 the carriage of the first machine (Fig. 5) is stepped to the next position or position 18 and the relay 150, upon deenergizing, at armatures 151 and 152 removes ground from conductors 201 and 202, thereby removing the short circuit around relay 238, whereupon the latter relay energizes in series with the locking circuits of relays 230 and 231. Relay 238, upon energizing, at armatures 252, 253, 254, 255, and 256 transfers the conductors 201, 202, 203, 204, and 205 from relays 230, 231, 232, 233, and 234 to magnets 224, 223, 222, 221, and 220, respectively. At armature 257 relay 238 prepares a circuit for relay 235 and a locking circuit for relay 236. Responsive to the operation of key 101, magnet 122 and relay 142 energize over the grounded conductor 200. Magnet 122 prepares the perforating means of the first machine to punch the inventory card in horizontal row 2 in vertical column 18 and relay 142 at armatures 153 and 156 grounds conductors 201 and 204 by way of conductor 116 and control springs 172. Responsive to the grounding of conductors 201 and 204, circuits may be traced for energizing magnet 224 and magnet 221 in series with relay 237 as follows: from grounded conductor 201, armature 252 and its working contact, magnet 224, winding of relay 237, terminal 278, and battery on lever 276; and from grounded conductor 204 by way of armature 255 and its working contact, magnet 221, and winding of relay 237 to battery at terminal 278 as previously traced. Relay 237, upon energizing, at armature 251 closes a circuit for energizing relay 236 and magnets 229 and 228. These magnets are operated practically simultaneously with magnets 224 and 221. Responsive to the operation of magnets 221, 224, 228 and 229 the perforating means of the punch shown in Fig. 6 is set to punch the merchandise card in horizontal rows 1, 4, 8, and 9 in vertical column 1 as indicated in Fig. 2. Relay 236, upon energizing, at armature 250 closes a locking circuit for itself in series with relay 235 by way of grounded armature 257 of the transfer relay 238. Relay 235 does not immediately energize because the same is short circuited from ground by way of armatures 251 and 257. When the operator releases the key 102 the magnet 122 and relay 142 de-energize. The deenergization of punch magnet 122 steps the carriage in the same manner as previously explained and the deenergization of relay 142 removes ground from conductors 201 and 204, thereby opening the circuits of magnets 224 and 221 and relay 237. Relay 237, upon deenergizing, at armature 251 removes the short circuit from around relay 235 and also opens the circuits of magnets 229 and 228, thereby causing such magnets to deenergize. Responsive to the deenergization of magnets 229, 228, 224 and 221 the carriage of the punch shown in Fig. 6 is permitted, due to its escapement, to take one step. When the short circuit around relay 235 is removed at armature 251, relay 235 energizes in series with the locking circuit of relay 236. At armature 249 relay 235 opens the circuit of relays 238, 239, and 231, whereupon said relays deenergize. At armature 257 transfer relay 238 opens the circuit of relays 235 and 236, whereupon such relays deenergize. At armatures 252 to 256, inclusive, transfer relay 238 transfers the conductors 201 to 205, inclusive, back into engagement with relays 230 to 234, inclusive. The relays and magnets of the punch shown in Fig. 6 are now in normal position ready for the next operation while

the carriage has been moved to position 2 in readiness to set the next row of perforating means to punch in the second vertical column of the merchandise card 10.

Responsive to the operation of key 101 magnet 121 and relay 141 energize from grounded conductor 200. Magnet 121 causes the perforating means to be set to punch the inventory card in horizontal row 1 in vertical column 19, and relay 141 at armatures 153 and 154 grounds conductors 201 and 203. Responsive to the grounding of conductors 201 and 203 relays 230 and 232 energize over a circuit similar to that previously traced for relays 230 and 231. At armatures 240 and 244 relays 230 and 232 prepare operating circuits 15 for magnets 229 and 227 and at armatures 238 and 243 relays 230 and 232 close locking circuits for themselves in series with transfer relay 238. Transfer relay 238 does not immediately energize because it is short circuited by ground extending over conductors 201 and 203. When key 101 is released the magnet 121 is deenergized to permit the carriage to move one step and relay 141 at armature 154 and armature 156 removes ground from conductors 201 and 203 thereby removing 25 the short circuit from around transfer relay 238 and permitting such relay to energize in series with the locking circuits of relays 230 and 232. Transfer relay 238 at armatures 252 to 256, inclusive, again transfers the leads 201 to 205, inclusive, from the relays direct to the magnets so that the next operation of a key in Fig. 5 operates the magnets direct instead of the relays. Responsive to the operation of key 110 magnet 130 is operated to prepare the perforating means to 30 punch the inventory cards in the zero horizontal row in vertical column 20 and relay 150 is energized to ground conductors 201 and 202 at armatures 151 and 152. The magnets 224 and 223 and relay 237 energize by way of grounded conductors 201 and 202 to battery at terminal 278. At armature 251 relay 237 closes the circuit for operating magnets 229 and 227 and also closes the circuit for energizing relay 236. The punch magnets 229, 227, 224, and 223 energize and set 45 the perforating means of the punch in Fig. 6 to punch the merchandise card in vertical column 2 as indicated in Fig. 2. When the operator releases the key 110 magnet 130 deenergizes, thereby causing the carriage of the punch in Fig. 5 50 to operate one step and relay 150 to remove ground from conductors 201 and 202 at armatures 151 and 152. When ground is removed from conductors 201 and 202 magnets 224 and 223 and relay 237 deenergize. At armature 251 relay 237 opens 55 the circuits of magnets 229 and 227 thereby permitting all of the magnets to release and step the carriage of the punch in Fig. 6 to its next position or in a position corresponding to the third vertical column of the merchandise card. At armature 251 relay 237 again removes the short circuit from around relay 235, thereby permitting such relay to energize in series with the locking circuit of relay 236. Relay 235, upon energizing, at armature 249 opens the circuit of 65 transfer relay 238 and relays 230 and 232, thereby permitting such relays to deenergize and return their various armatures to normal position. The circuits of relays 235 and 236 are opened at armature 251 by the deenergization of relay 238. All 70 of the apparatus in Fig. 6 is now in normal position with the exception of the carriage which is now in position 3. When the carriage of the punch shown in Fig. 5 moves into position 21 the control bar 171 opens the control springs 172 so that 75

the relays in Fig. 5 do not control the punch in Fig. 6 while the punch in Fig. 5 is punching in columns 21, 22, 23, 24, and 25. By the operation of the proper keys the cost price of the article by 5 the punch in Fig. 5 is set in the proper rows of the perforating means in an obvious manner and it is thought that this operation need not be explained because it is the same as heretofore described. When the carriage of the punch shown 10 in Fig. 5 reaches its twenty-sixth position the control bar 171 again closes the control springs 172 so that the relays in Fig. 5 may control the punch in Fig. 6.

The operator now operates the keys in accordance with the sales price and the punch in Fig. 5 and the punch in Fig. 6 are operated in a manner similar to that described to prepare the perforating means to punch the inventory card 11 and the merchandise card 10 as shown in Figs. 2 and 3. 15 Since the operation of the two punches is practically similar to that previously described, it is believed that further explanation is deemed unnecessary when it is understood that the punch in Fig. 6 is only controlled during the time that the control bar 171 closes the control springs 172. It will be noted that the punch in Fig. 6 stores the first digit on the relays such as relays 230 to 234 while the punch in Fig. 5 is setting the perforating means responsive to the first operation 20 of a key and that when a second key is operated the punch in Fig. 5 sets the perforating means of the next or second set and this time causes circuits to be closed to Fig. 6 so that four magnets (two of which have been previously prepared by 25 the storing relays) are operated to set the perforating means of one row or set to punch the merchandise card with four perforations in a single vertical column. By remembering that the magnets in Fig. 6 punch holes in horizontal rows 30 in accordance with the last digits of their reference characters it can be plainly seen by consulting the chart in Fig. 4 that the merchandise card shown in Fig. 2 will be punched in the manner as indicated in Fig. 2 responsive to the operation of 35 the proper keys. After completely setting the various sets of perforating means the operator will operate the trip key TR, thereby closing a circuit for energizing relay 179 as follows: from grounded conductor 200, trip springs TR, relay 40 179, conductor 100, and terminal 178 to battery. Trip relay 179, upon energizing, at armature 180 permits the tensioned spring 192 to rotate the flange 194 into engagement with the rotating flange 195 by operating armature 180 out of the 45 path of the pin 193. The spring 192 turns the flange 194 upon its threads so that flange 194 engages the rotating flange 195 thereby causing the shaft 185, the interrupter 184 and flange 190 to rotate with the shaft 196. The rotation of 50 shaft 185 causes the card to be perforated in accordance with the pins or perforating means which have been set and locked responsive to the operation of the magnets as previously described. After the cards have been punched the operator 55 may operate the carriage return key CR, or in case she does not, the interrupter 184 will be rotated so as to complete a circuit between springs 182 and 183, for the purpose of energizing the carriage return relay. In either case relay 173 is 60 energized from grounded conductor 200 by way of the carriage return springs CR, or springs 182 and 183, to the winding of relay 173 and battery. By the operation of armature 174 relay 173 permits the lever 176 to be operated by spring tension 65 so that the battery connected to lever 176

is disengaged from terminal 178 and is connected to terminal 177. Due to this operation a circuit may be traced from ground at wiper 188, through the copper band on the magnetic clutch and through the winding of the magnetic clutch to 5 the copper band, which is engaged by wiper 186, terminal 177 and battery on lever 176. Due to the energization of the winding of the magnetic clutch the magnetic clutch 189 is magnetically held in engagement with the rotating disc 190 thereby causing the clutch to wind up the tape 10 187 to cause the carriage of the punch to be returned to its normal position. The return of the carriage to normal position causes all of the pins which have been locked in operated position to 15 be returned to their normal position in a manner similar to that described in the Patent No. 1,643,779, issued September 27, 1927, to W. W. Lasker. When the carriage return relay 173 operated its armature 174 lever 176 opened the circuit of trip relay 179, thereby permitting the latter relay to drop its armature 180 in the path of the rotating pin 193. When the carriage of the punch shown in Fig. 5 has been returned to its normal position, arm 175 strikes the lever 176 20 to cause it to disengage from terminal 177 and engage with terminal 178. At this time the wipers 182 and 183 of the interrupter no longer complete the circuit for relay 173 and therefore armature 174 is allowed to drop in position to 25 hold the lever 176 in the position shown in the drawings until relay 173 is again actuated. By the disengagement of the lever 176 from terminal 177 the circuit through the winding of the magnetic clutch is opened and the carriage remains 30 in normal or its home position until again actuated by its escapement. The two shafts 185 and 196 continue to rotate until the pin 193 strikes the armature 180 which causes the screw flange 194 to 35 screw away from and disengage from the flange 40 195. Due to the construction and weight of the shaft 185 the shaft 185 rotates a little further or only a sufficient distance to tension the spring 192 so that it may again operate the flange 194 when trip relay 179 is again actuated. All of the 45 apparatus of the punch shown in Fig. 5 is now in normal position and may now be used for punching a different inventory card it being understood that a new card has been positioned in punching position in the manner described in the aforesaid 50 Lasker patent.

The operation of the trip key TR in addition to closing a circuit for the trip relay 179 also closes a circuit over conductor 206 to the trip magnet 279 in Fig. 6. The carriage return relay 55 273 is also operated over conductors 200 and 207 in a manner similar to the operation of carriage return relay 173 and it is believed that it can be readily seen that the carriage of the punch shown in Fig. 6 is returned to its normal position in a 60 manner similar to that described for the punch carried in Fig. 5.

The invention having been fully described, what is considered new and is desired to have protected by Letters Patent will be pointed out in 65 the appended claims.

What is claimed is:

1. In a card perforating system, two card perforating mechanisms each having a carriage operated step by step to successive setting positions, 70 a single set of keys for controlling the operation of both said mechanisms, means for moving the carriage of the first mechanism to successive setting positions responsive to each successive operation of said keys, and means for moving the 75

carriage of the second mechanism to successive setting positions responsive to only each successive second operation of said keys.

2. The combination of two card perforating machines, of a single set of keys for controlling the perforating selections of both said machines, of means responsive to an operation of one of said keys for causing the first of said machines to perform a punch selecting operation in accordance with the actuated key, and means responsive to a subsequent operation of another one of said keys for causing said first machine to perform a punch selecting operation in accordance therewith and for causing the second of said machines to perform a punch selecting operation in accordance with the operation of both said keys.

3. In a card punching machine, sets of perforating means, a plurality of magnets for controlling the setting of the perforating means, a set of keys for controlling said magnets to set the perforating means to punch cards, and means for operating said machine in two stages to set its perforating means to punch a card with a plurality of perforations in a single punching operation, the actuation of a key during the first of said stages selecting a plurality of said magnets for operation responsive to the actuation of a key during the second of said stages and the operation of said key during the said second stage completing the operation of said selected magnets and operating an additional plurality of said magnets.

4. In a card perforating system, a plurality of card punching machines and perforating means therefor, a plurality of magnets for controlling the setting of the perforating means in each of said machines, a single set of keys for controlling said magnets, means responsive to the operation of one of said keys for operating one of said magnets in the first of said machines and for preparing a plurality of the magnets in the second of said machines for operation, and means responsive to a subsequent operation of one of said keys for operating one of said magnets in the first of said machines, for operating the said prepared magnets in the second of said machines and for operating an additional plurality of said magnets in the second of said machines.

5. The combination of two card perforating machines, of perforating means and a single set of keys for controlling the perforating selections of both said machines, of a storage device associated with the second of said machines, means responsive to the operation of one of said keys for setting the perforating means of the first of said machines in accordance therewith and for setting said storage device in accordance with the actuated key, and means responsive to another operation of one of said keys for setting the perforating means of said first machine in accordance therewith and for setting the perforating means of said second machine in accordance with the setting of said storage device and in accordance with the last actuated key.

6. In a card perforating machine, perforating means, a control key, a magnet for setting a perforating means, a circuit for said magnet, a storage relay adapted when energized to prepare the circuit of said magnet, a circuit for energizing said storage relay completely responsive to the actuation of said control key, a transfer relay energized responsive to the opening of said storage relay circuit, a control relay for completing the energizing circuit of said magnet, a second perforating setting magnet, and a circuit

for energizing said control relay and said second magnet placed under the control of said key by said transfer relay.

7. In a plurality of card punching machines, a control key, a perforating control magnet in a first one of said machines, a perforating control magnet in a second one of said machines, a circuit for the second of said magnets, a storage relay adapted when energized to prepare the circuit for energizing said second magnet, a circuit for energizing said first magnet and a circuit for energizing said storage relay completed responsive to the first actuation of said key, a transfer relay energized in series with said storage relay responsive to the release of the actuated key, a control relay for completing the energizing circuit of said second magnet, another perforating control magnet in the second of said machines, and a circuit for energizing said control relay and said other magnet placed under control of said key by the energization of said transfer relay whereby a second operation of said key completes the circuit for energizing said control relay and said other magnet and the energization of the control relay completes the circuit for energizing said second magnet.

8. In a card perforating machine, perforating means, a plurality of magnets for controlling the perforating means to punch statistical cards, a set of storage devices for preparing a portion of said magnets for operation, a set of control keys for controlling said storage devices and said magnets, a transfer device for shifting the control of said keys from said storage devices to a plurality of said magnets, means for operating a portion of said storage devices when a key is actuated, and means for operating said transfer device when the key is restored.

9. In a card perforating machine for punching statistical cards, a set of control keys, a storage device comprising a set of storage relays, a set of conductors normally connected to said storage relays, a set of perforating control magnets, and a transfer relay and circuits effective to disconnect the said storage relays from said conductors and to connect said magnets to said conductors whenever a control key is operated and released.

10. In a recording machine, a storage device, a plurality of magnets controlled by said storage device, a set of conductors normally extending to said storage device, other magnets, means for operating the storage device over said conductors and for thereafter transferring said conductors to said other magnets, and means for operating some of said other magnets directly over said conductors and for simultaneously operating certain of said plurality of magnets in accordance with the operated storage device, and means responsive thereto for thereafter transferring said conductors back to said storage device.

11. In a plurality of recording machines, a control key, a recording magnet in the first machine, a recording magnet in the second machine, a storage relay, a transfer relay, and a control relay associated with said machines, means for energizing the first magnet responsive to each actuation of said key, means for energizing said storage relay to prepare said second magnet for operation responsive to the first actuation of said key, means for energizing said transfer relay and for maintaining said storage relay energized responsive to the release of said key, another recording magnet in the second machine, means operated by the energization of said transfer relay for preparing said control relay and said other

magnet for operation, means for energizing said control relay and said other magnet responsive to the second actuation of said key, and means for energizing the said second magnet responsive to the energization of said control relay.

12. In a card perforating machine, a plurality of rows of perforator selecting means, corresponding perforating means therefor, each of said perforator selecting means adapted when operated to control a corresponding perforating means to perforate a card with a single perforation, each of said rows comprising a first and a second group of said perforator selecting means, a plurality of devices, each device respectively representing certain information, means responsive to the actuation of any one of said devices for selecting a plurality of said perforator selecting means in certain combinations in the first group of the first row, means responsive to another actuation of any one of said devices for selecting a plurality of said perforator selecting means in certain combinations in the second group in the first row, said selected perforator selecting means operating the corresponding perforating means to perforate a card with combinational perforations in accordance with the devices actuated.

13. In a card perforating machine, a plurality of rows of perforator selecting means and corresponding perforating means, each of said perforator selecting means adapted when operated to control a corresponding perforating means to perforate a card with a single perforation, each of said rows comprising a first and a second group of said perforator selecting means, a plurality of devices, each device respectively representing certain information, means responsive to the actuation of any one of said devices for selecting a plurality of said perforator selecting means in certain combinations in the first group of the first row, means responsive to another actuation of any one of said devices for selecting a plurality of said perforator selecting means in certain combinations in the second group in the first row, and means responsive to the actuation of the last mentioned one of said devices for operating said selected perforator selecting means in the first row to select corresponding perforating means and for rendering the perforator selecting means in the second of said rows selectable by said devices.

14. In a card perforating machine, successive rows of perforator selecting means, each row including a first and a second group of said perforator selecting means, a plurality of devices, each device representing certain information, means for selecting a perforator selecting means in the first group of a row responsive to the first operation of any one of said devices, means for operating the selected perforator selecting means in the first group and for operating a perforator selecting means in the second group of such row responsive to a second operation of any one of said devices, means operated responsive to said second operation for rendering the next row of said perforator selecting means selectable, and means for perforating a card with coded information in accordance with the operated ones of said perforator selecting means.

15. In a card perforating machine for perforating cards, perforator selecting means arranged in successive columns, each of said columns divided into two sections, keys representing data, a carriage for rendering successive columns of said perforator selecting means selectable, means for selecting a perforator selecting means in the first

section of the first column in response to the first actuation of any one of said keys and for selecting a perforator selecting means in the second section of the first column in response to a second actuation of one of said keys, means responsive to said last selection for shifting said carriage to render the second column of perforator selecting means selectable in response to subsequent actuations of said keys and perforating means controlled by the selected perforator selecting means for perforating a card with data perforations.

16. In a card perforating machine for perforating cards with coded perforations, perforator selecting means arranged in successive columns and each column containing a plurality of groups of said perforator selecting means, devices representing data, a carriage for rendering successive columns of said perforator selecting means selectable, means for selecting a plurality of perforator selecting means in the first group of the first column in response to the first actuation of any one of said devices and for selecting a plurality of perforator selecting means in the second group of the first column in response to a second actuation of any one of said devices, means responsive to each second selection for shifting said carriage to render the next succeeding column of perforator selecting means selectable in response to subsequent actuations of said devices, and perforating means controlled by the selected perforator selecting means for perforating a card with coded data perforations in fields in perforation spaces thereon.

17. In a card perforating machine for perforating cards, perforator selecting means arranged in rows and divided into a first and second group, devices representing data, means responsive to each odd successive operation of any one of said devices for selecting perforator selecting means in the first group of each successive row, means responsive to each even successive operation of any one of said devices for selecting perforator selecting means in the second group of each successive row, and means for perforating a card in accordance with said selections and the successive operated devices.

18. In a card perforating system, a first card perforating machine having successive rows of perforator selecting means, a second card perforating machine having successive rows of perforator selecting means divided into first and second groups, devices representing data, means responsive to each odd actuation of one of said devices for selecting a single perforator selecting means in successive odd rows in the first machine and a plurality of perforator selecting means in each row in the first group in the second machine, means responsive to each even actuation of one of said devices for selecting a single perforator selecting means in successive even rows in the first machine and a plurality of perforator selecting means in each row in the second group in the second machine, and means for perforating a card in the first machine and a different sized card in the second machine in accordance with said selections with corresponding information but with non-corresponding perforations.

19. In a card perforating system, a first and a second card perforating machine each having rows of perforator selecting means therein, devices representing data, means for selecting a single perforator selecting means in the first row in the first machine and a plurality of perforator selecting means in a portion of the first

row in the second machine in response to the first operation of any one of said devices and for selecting a single perforator selecting means in the second row of the first machine and a plurality of perforator selecting means in the remaining portion of the first row of the second machine in response to the second operation of any one of said devices, perforating means in both machines, and means for simultaneously operating said perforating means in said machines in accordance with said selections to perforate a card in the first machine with single perforations in successive rows and a smaller card in the second machine with combinational perforations whereby said cards are perforated with corresponding information but non-corresponding perforations in accordance with the devices operated.

20. In a card perforating system, a first and a second card perforating machine each having rows of perforator selecting means therein, devices representing data, a carriage for each machine for rendering successive rows of said perforator selecting means selectable, means responsive to each odd actuation of any one of said devices for selecting a single perforator selecting means in successive odd rows of the first machine and a plurality of perforator selecting means in a portion of each successive row of the second machine and for thereafter operating the carriage of the first machine to render successive even rows of perforator selecting means in the first machine selectable, means responsive to each even operation of any device for selecting a single perforator selecting means in successive even rows of the first machine and a plurality of perforator selecting means in the remaining portions of each successive row in the second machine and for thereafter operating the carriage of the first machine to render the succeeding odd row of perforator selecting means therein selectable and the carriage of the second machine to render the next succeeding row of perforator selecting means therein selectable, perforating means in both machines, and means for simultaneously operating the perforating means in said machines in accordance with said selections to perforate a card in the first machine with single perforations and a smaller card in the second machine with combinational perforations whereby said cards are simultaneously perforated with corresponding information but non-corresponding perforations in accordance with the devices actuated.

21. In a card perforating machine, a plurality of rows of perforating means, each of said perforating means adapted to perforate a card with a single perforation, each of said rows comprising a first and a second group of perforating means, perforator selecting means individual to each perforating means and correspondingly divided into rows and groups, a device, means responsive to the actuation of said device at given times for selecting a plurality of perforating selecting means in a certain combination in any one of said first groups of perforator selecting means, means responsive to the actuation of said device at different predetermined times for selecting a plurality of perforator selecting means in a certain combination in any one of said second groups of perforator selecting means, said selected perforator selecting means controlling their corresponding perforating means to perforate a card with combinational perforations in accordance with the actuations of said device.

22. In a card perforating machine, a plurality

of rows of perforating means, each of said perforating means adapted to perforate a card with a single perforation, each of said rows comprising a first and a second group of perforating means, the first groups of perforating means corresponding to a first punching field on a card and the second groups of perforating means corresponding to a second punching field on such card, perforator selecting means individual to each perforating means and correspondingly arranged in rows and groups, a device, means responsive to the actuation of said device at given times for selecting a plurality of perforator selecting means in a certain combination in any one of said first groups of perforator selecting means, means responsive to the actuation of said device at different predetermined times for selecting a plurality of perforator selecting means in a certain combination in any one of said second groups of perforator selecting means, said selected perforator selecting means in said first groups controlling corresponding perforating means in their first groups to perforate a card with combinational perforations in the first field and said selected perforator selecting means in said second groups controlling corresponding perforating means in their second groups to perforate such card with combinational perforations in the second field in accordance with the actuations of said device.

23. In a card perforating machine for perforating a card having two fields, the combination of a plurality of rows of perforating means, each row comprising a first and a second group of perforating means, said first groups of perforating means corresponding to the first field on the card and said second groups of perforating means corresponding to the second field on the card, a first group of magnets, a second group of magnets, a group of coding devices, a set of keys, and transfer means operable from a non-operated to an operated position; said coding devices operating responsive to the actuation of any of said keys to operate the first group magnets in case said transfer means is in its non-operated position or to actuate said second group magnets in case said transfer means is in its operated position, said first group magnets operated to select the perforating means in said first groups, said second group magnets operated to select the perforating means in said second groups, said selected perforating means in said first groups operated to perforate a card in the first field and said selected perforating means in said second groups operated to perforate such card in the second field in accordance with the actuations of said keys.

24. In a card perforating machine for perforating cards, perforating means arranged in columns, each of said columns divided into two sections for perforating a card in two fields, perforator selecting means individual to each perforating means and correspondingly divided into two sections, devices representing data, means including a carriage for rendering successive columns of said perforator selecting means selectable, means responsive to the actuation of any of said devices at given times for selecting perforator selecting means in said first sections, means responsive to the actuations of the same or different ones of said devices at different predetermined times for selecting perforator selecting means in said second sections, said selected perforator selecting means in said first sections controlling their corresponding perforating means to perforate a card in one field with data perforations and said selected perforator selecting means in

said second sections controlling their corresponding perforating means to perforate such card in the other field with data perforations in accordance with the actuations of said devices.

- 5 25. In a punching machine, successive rows of perforator selecting means, each row including a first and a second group of perforator selecting means, a carriage operable step-by-step from successive positions to prepare successive rows 10 of perforator selecting means for operation, a first group of magnets corresponding in number to the number of perforator selecting means in a first group of a single row, each magnet in said first group operable to control the setting of a corresponding perforator selecting means in each of said first groups when said carriage is stopped in the positions to prepare such perforator selecting means for operation, a second group of magnets corresponding in number to the number of 15 perforator selecting means in a second group of a single row, each magnet in said second group operable to control the setting of a corresponding perforator selecting means in each of said second groups when said carriage is stopped in the positions to prepare such perforator selecting means 20 for operation, and means including a set of keys for controlling the operation of both said groups of magnets, said last means operable in two stages to transfer the control of the keys from the first 25 group magnets to the second group magnets, the first group magnets selected for operation in the first stage responsive to certain actuations of said keys and the selected first group magnets and the second group magnets operated in the second 30 stage responsive to certain other actuations of the same or different keys.

26. In a marking machine, successive rows of marker operating means, each row including a first and a second group of marker operating 40 means, a first group of magnets, each magnet in said group controlling means to set a corresponding marker operating means in each of said first groups, a second group of magnets, each magnet in said second group controlling means to set a 45 corresponding marker operating means in each of said second groups, means including a single set of keys for controlling said magnets in both said groups to set said marker operating means in code combinations in any one of said groups, and 50 means for operating said machine in two stages to set its groups of marker operating means to mark in code combinations with a plurality of marks in a single marking operation, the first of said stages controlling the operation of said 55 magnets in the first group responsive to certain actuations of said keys and the second of said stages controlling the operation of said magnets in the second group responsive to certain other actuations of the same or different ones of said 60 keys.

27. In a marking machine, successive rows of marker selecting means, each row comprising a first and a second group of said marker selecting means, a plurality of devices, each device representing certain information, means for selecting a plurality of said marker selecting means in the first group of a row responsive to the first operation of any one of said devices, means for operating the selected marker selecting means in the first group and for operating a plurality of said marker selecting means in the second group of said row responsive to another operation of any one of said devices, means operated responsive to said other operation for rendering the next 70 row of said marker selecting means selectable, 75

and means for marking a record with coded information in accordance with the operated ones of said marker selecting means.

28. In a recording system, a first marking machine having marking means for marking a record 5 with single marks designating characters, a second marking machine having marking means for marking a smaller record with a plurality of combinational marks designating characters, the number of marking means required in the second 10 machine being less than the number of marking means required in the first machine, a corresponding marker selecting means for each marking means, means common to both machines for controlling the selection of the marker selecting means of each machine, means responsive to an operation of the common means for selecting a single marker selecting means of the first machine and a plurality of marker selecting means of the second machine, and means for simultaneously operating the marking means in said machines in accordance with said selections to mark the first record with single marks and the smaller record with combinational marks whereby said records are marked with corresponding information but non-corresponding perforations.

29. In a recording system, a plurality of recording mechanisms, successive groups of marking devices in each mechanism, a set of contacting means for controlling the selections of said 30 marking devices, and means responsive to the actuation of a first and a second of said contacting means for selecting marking devices in each of two groups in one of said mechanisms and for selecting marking devices in code combinations 35 in only a single group in another of said mechanisms.

30. In a recording system, a recording mechanism having a carriage operated step by step to successive setting positions, a plurality of contacting means for controlling the operation of said mechanism, and means for moving the carriage of said mechanism to successive setting positions responsive to only each successive second 40 operation of any of said contacting means. 45

31. In a recording machine, the combination of marking means and a single set of contacting means for controlling the selections of said marking means, of a storage device, means responsive to the operation of one of said contacting means 50 for setting said storage device in accordance with the actuated contacting means, and means responsive to another actuation of one of said contacting means for setting the marking means in accordance with the setting of said storage device 55 and in accordance with the last actuated contacting means.

32. In a machine for marking records, a set of devices one for each character employed in marking a record, a storage device comprising storing 60 relays electrically operated by actuations of the same or different ones of said devices for storing characters corresponding to the devices actuated, marking mechanism, and transfer means operable in response to subsequent actuations of the 65 same or different ones of said devices for transferring said stored characters from said operated storage relays to set said marking mechanism to subsequently mark the record in accordance with the actuated devices.

33. In a machine for marking records, a set of devices one for each character employed in marking a record, storage means operated by a plurality of actuations of the same or different ones of said devices for storing characters correspond- 75

ing to the actuated devices, mark selecting mechanism, transfer means operable in response to subsequent actuations of the same or different ones of said devices for transferring said stored 5 characters from said storage device to set said mark selecting mechanism in accordance with the actuated devices, and marking means thereafter operable in accordance with the set mark selecting mechanism for marking the record in 10 accordance with said plurality of actuated devices.

34. In a recording machine for marking records, a plurality of marking means for marking a record, a marker selecting means for each 15 marking means, magnets for operating the marker selecting means, a storage device, a plurality of contacting means each corresponding to certain information, storage relays having contacts in said device operated in response to the 20 actuation of one of said contacting means for storing the information corresponding to the actuated contacting means, circuits subsequently completed through the contacts of the operated storage relays in response to a subsequent actuation of one of said contacting means for operating the magnets in accordance with the previously 25 actuated contacting means, a plurality of said marker selecting means operated by the operated ones of said magnets, and means for thereafter 30 operating said marking means in accordance with the operated marker selecting means to mark a record.

35. In a recording apparatus, two sets of marking elements each arranged in rows both longitudinally and transversely, corresponding transverse rows of each set being in alignment, a set of controlling devices one for each character employed in said recording apparatus, and means responsive to a plurality of operations of the 35 same or different ones of said devices for setting the marking elements in each of the two corresponding aligned transverse rows, the two aligned transverse rows thereby having marking elements set in accordance with a plurality of characters to be recorded.

36. In a recording apparatus, two sets of marking elements each arranged in rows both longitudinally and transversely, corresponding transverse rows of each set being in alignment, a set of 40 controlling devices one for each character employed in said recording apparatus, means responsive to a plurality of operations of the same or different ones of said devices for setting the marking elements in each of the two corresponding aligned transverse rows, the two aligned transverse rows thereby having marking elements set in accordance with a plurality of characters to be recorded, and means for thereafter 45 causing the set marking elements to record the 50 characters corresponding to the actuated devices.

37. In a recording apparatus, marking elements arranged in rows both longitudinally and transversely, each transverse row divided into two sets of marking elements, a set of controlling devices one for each character employed in said recording apparatus, means responsive to successive operations of the same or different ones of said devices for setting the marking elements in said sets successively to thereby set the marking elements in both sets in each transverse row, each such operation of any one of said devices 55 controlling only the setting of the marking elements in one set, and each transverse row thereby having marking elements set in accordance with a plurality of characters to be recorded, and

means operated thereafter to cause said set marking elements to record the characters corresponding to the actuated devices.

38. In a recording apparatus, rows of marker selecting elements, a set of controlling devices 5 one for each character employed in said recording apparatus, means responsive to the actuation of any one of said devices at one time for selecting certain marker selecting elements in one of said rows, means responsive to the actuation of 10 any one of said devices at another time for setting the selected marking elements and certain other marker selecting elements in the same row, and marking means operated thereafter in accordance 15 with said set marker selecting elements to record the characters corresponding to the actuated devices.

39. In a machine for recording data, a plurality of rows of marking means, each marking means adapted to mark an object with a single 20 mark, each of said rows comprising a first and a second group of marking means, said object having two fields corresponding respectively to the first and second groups of said marking means, and means for operating a combination of marking 25 means in any one of said first groups for a given character to thereby mark data in the field corresponding to said first groups and for operating a combination of marking means in any one of said second groups for said given character 30 to thereby mark data in the other field corresponding to the said second groups.

40. In a machine for marking records, successive rows of marker selecting means, each row including a first and a second group of marker 35 selecting means, a carriage operable step by step from successive positions to prepare successive rows of marker selecting means for operation, a first group of magnets corresponding in number to the number of marker selecting means in a 40 first group of a single row, each magnet operable to control the setting of a corresponding marker selecting means in each of said first groups when said carriage is stopped in the positions to prepare such marker selecting means for operation, a 45 second group of magnets corresponding in number to the number of marker selecting means in a second group of a single row, each magnet in said second group operable to control the setting of a corresponding marker selecting means in 50 each of said second groups when said carriage is stopped in the positions to prepare such marker selecting means for operation, and means for operating said machine in two stages to set its groups of marker selecting means to mark in 55 code combinations, the first stage controlling the operation of said magnets in the first group and the second stage controlling the operation of said magnets in the second group.

41. In a punching machine, two groups of 60 selecting magnets, a group of storage relays controlling the magnets of one group, a set of keys controlling said relays and the magnets of the other group, and means for automatically shifting the control of said keys from the said relays to 65 said magnets and back again responsive to successive key operations.

42. In a recording apparatus, marker selecting elements arranged in rows both longitudinally and transversely, a plurality of setting means corresponding in number to the number of marker selecting means in each transverse row, each setting means corresponding to a longitudinal row and adapted to be operated to set any marker selecting element in such longitudinal row, a plu- 75

5 rality of controlling devices one for each character employed in said recording apparatus, each device corresponding to a plurality of marker selecting elements in each transverse row, means for selecting a plurality of said setting means and for operating the same in response to a plurality of actuations of said character devices to set the marker selecting elements corresponding to the

actuated devices in only one of said transverse rows, and marking means operated thereafter in accordance with the set marker selecting elements to record the characters corresponding to the actuated devices in a single row corresponding to 5 said one transverse row.

LOUIS FRANK WOODRUFF.
MARTIN L. NELSON.
